US00D881365S

(12) **United States Design Patent** (10) **Patent No.:** **US D881,365 S**
Mecker et al. (45) **Date of Patent:** **** Apr. 14, 2020**

(54) **DISPENSER**

(71) Applicant: **S. C. JOHNSON & SON, INC.**,
Racine, WI (US)

(72) Inventors: **Alex Mecker**, Chicago, IL (US); **Peter Borowski**, Lake Bluff, IL (US); **Nick Rees**, New York, NY (US)

(73) Assignee: **S. C. Johnson & Son, Inc.**, Racine, WI (US)

(**) Term: **15 Years**

(21) Appl. No.: **29/638,732**

(22) Filed: **Feb. 28, 2018**

(51) LOC (12) Cl. **23-04**

(52) U.S. Cl.

USPC **D23/366**; D23/386

(57) **CLAIM**

The ornamental design for a dispenser, as shown and described.

DESCRIPTION

FIG. 1 is an isometric view of a top, front, and right side of an ornamental design for a dispenser;

FIG. 2 is a front elevational view of the dispenser of FIG. 1; FIG. 3 is a rear elevational view of the dispenser of FIG. 1; FIG. 4 is a right side elevational view of the dispenser of FIG. 1;

FIG. 5 is a left side elevational view of the dispenser of FIG. 1;

FIG. 6 is a top plan view of the dispenser of FIG. 1; and, FIG. 7 is a bottom plan view of the dispenser of FIG. 1. The broken lines are included for the purpose of illustrating portions that form no part of the claimed design.

1 Claim, 6 Drawing Sheets
